US00D384164S

United States Patent [19]

Leiva et al.

[11] Patent Number: Des. 384,164

[45] Date of Patent: **Sep. 23, 1997

[54] **TRANSPARENT ASSAY TESTER FOR BIOLOGICAL FLUIDS**

[75] Inventors: William A. Leiva, Half Moon Bay; Ian D. Wells, Escondido, both of Calif.

[73] Assignee: Medix Biotech, Inc., San Carlos, Calif.

[**] Term: 14 Years

[21] Appl. No.: 37,222

[22] Filed: Apr. 6, 1995

Related U.S. Application Data

[63] Continuation-in-part of Ser. No. 15,399, Nov. 15, 1993, abandoned, which is a continuation of Ser. No. 918,340, Jul. 21, 1992, abandoned.

[51] LOC (6) Cl. 24-02

[52] U.S. Cl. D24/224; D24/223; D25/225
